Walter S. Adams, Inventor
By his Attorney, L. Levy

UNITED STATES PATENT OFFICE.

WALTER S. ADAMS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

CAR-TRUCK.

1,104,761.

Specification of Letters Patent. Patented July 28, 1914.

Application filed September 5, 1913. Serial No. 788,191.

To all whom it may concern:

Be it known that I, WALTER S. ADAMS, a citizen of the United States, and resident of Philadelphia, in the county of Philadelphia and State of Pennsylvania, and whose post-office address is care of The J. G. Brill Co., Sixty-second street and Woodland avenue, in said city, have invented certain new and useful Improvements in Car-Trucks, of which the following is a specification.

My invention relates to improvements in swing bolster car trucks, and particularly to that class wherein semi-elliptical or leaf springs, or other equivalent form of bolster supports, are carried from the side frames of the truck by swinging links or hangers, and in which the bolster is supported on said leaf springs, etc., by other springs.

My present invention consists in certain details of construction and combination of parts hereinafter described, and finally pointed out in the claims.

In the drawing, forming part of this specification, Figure 1 is a side elevation showing a portion of the side frame of the car truck and the improved bolster connection supported therefrom. Fig. 2 is a side elevation, partly in section, on the line 2—2 of Fig. 1, of a portion of the bolster and side-frame, and the spring connection between the leaf spring and the bolster. Fig. 3 is a section on the line 3—3 of Fig. 2, looking in the direction of the arrows, and Fig. 4 is a section on the line 4—4 of Fig. 2.

Similar reference characters designate like parts throughout the several views.

For the purpose of describing my invention, I have not deemed it necessary to illustrate an entire truck construction, as those skilled in the art are familiar therewith. However, for the purpose of further illustration, reference is made to the truck shown in patent granted to me on the 14th day of October, 1913, Ser. No. 1,076,009.

In the drawing, 1 is an intermediate portion of the side-bar or upper chord of the car truck. This is usually provided with pedestals of conventional or desired construction. It will be understood that all of

the parts hereinafter described, except the intermediate section of the bolster, are duplicated at each side of the truck, the pedestals engaging axle boxes, which hold axles and wheels in the usual manner. The sidebar or upper chord is connected transversely by the usual transoms 2 shown in dotted lines in Fig. 1.

At 3 are hangers comprising pendant side pieces 4, which hangers embrace the side-bars and rest on their upper ends 5 on bearings 6, the lower ends 7 carrying blocks 8 forming spring seats. A form of hanger of the class described is shown in my said patent.

At 9 is the semi-elliptic leaf spring, which, in the present case, is arched upwardly and its ends provided with projectus 10 (in dotted lines) engaging the spring seats 8. As above stated, it will be understood that there are to be two of such springs, one on each side of the truck, and disposed longitudinally below the side bars 1.

At 11 is the bolster shown in the present case as a casting having an enlarged intermediate section 12 adapted to pass between the transoms 2 and outer ends or extensions 13 passing underneath and clearing the side bars of the truck frame. The bolster may be cast with the top and bottom flanges 14, 15 connected by the web 16 and the lower web has a pendant lug 17 provided with an opening for the passage of a bolt. The bolster ends comprise a horizontal web 18, having at each side and front and rear pendant flanges 19, 20 by means of which spring-seats are formed.

The leaf-springs 9 are provided with the usual strap or band 21 at their arches, and upon this band is seated the extension 13 which forms a link or spring-seat consisting of a casting 22 having a lower web 23 with an elevated rectangular recess 24 in front embracing the said strap, side webs 25 and a wall 26 constituting, with the side walls 25 and rib 27 a spring seat. The link or spring seat 13—22 has inwardly extending projections or ears 28 between which the lug 17 extends and which are pivotally se-

cured together by the pin 29. The links constitute continuations of the bolster ends, and serve to connect the springs 9 on each side of the truck. Extending between the respective spring seats is a coil or spiral spring 30 which lies within the said leaf springs and between them and the pivot pin 29. The bolster is thus supported on the leaf spring by further springs which are arranged inside of the leaf springs, thereby providing for a resilient support of the bolster on the leaf springs, the inner end of the link 22 lying within the plane of the bolster, and movably engaging it to restrain excessive movement on the spiral springs in either direction, while at the same time permitting of the usual movement of the bolster on the spiral springs in taking and relieving the leaf springs of the car load. Displacement between the connections in the direction of the length of the leaf springs is prevented by the possible engagement of the flanges, ears 28 and lug 17, there being sufficient play allowed between them for all practical purposes, without engagement.

Within the scope of the appended claims, my invention may be variously embodied without departing from its spirit.

Having described my invention, I claim:

1. In a car truck, the combination with a truck frame, body supporting springs supported on the truck frame, a truck bolster, links or spring seats extending from the said body supporting springs and movably connected with the bolster, and further springs extending between the links or spring seats and the bolster at a point between the body supporting springs and the said movable connection.

2. In a car truck, the combination with a truck frame, body supporting springs supported on the truck frame outside of the wheel gage, a truck bolster, links or spring seats extending from the said body supporting springs and movably connected with the bolster, and further springs extending between the links or spring seats and the bolster at a point within the wheel gage and between the body supporting springs and the said movable connection.

3. In a car truck, the combination with a truck frame, leaf springs supported on the truck frame, links or spring seats extending from the leaf springs, a truck bolster, means for movably connecting the inner ends of the said links or spring seats with the bolster, and a spring extending between said links or spring seats and the bolster at a point between said leaf springs and said movable connection.

4. In a car truck, the combination with a truck frame, longitudinally disposed leaf springs supported on the truck frame, links or spring seats extended inwardly from the spring seats, a cross bolster, means for mov-

ably connecting the bolster with said links, and a spring extending between each of said links and the bolster at a point between the leaf springs and said movable connection.

5. In a car truck, the combination with a truck frame, longitudinally disposed leaf springs supported by the truck frame, links or spring seats extending inwardly from said leaf springs, a cross bolster, means for movably connecting the bolster to said links, and an upwardly disposed spiral spring extending between each of said links and the bolster at a point between the leaf springs and said movable connection. 70

6. In a car truck, the combination with a truck frame having side bars, hangers thereon, longitudinally disposed leaf springs supported from the side bars by the hangers, links or spring seats extending inwardly from said leaf springs, a cross bolster, means for movably connecting the bolster with said links, and a spiral spring extending between each of said links and the bolster between the leaf springs and said movable connection. 80

7. In a car truck, the combination with the truck side bars, hangers pendant therefrom, longitudinally disposed leaf springs supported by the hangers, a cross bolster, links or spring seats secured at their outer ends to the leaf springs and at their inner ends movably secured to the bolster, and further springs extending between the said links and bolster between the said leaf springs and the said movable connection. 90

8. In a car truck, the combination with the side bars, hangers pendant therefrom, longitudinally disposed leaf springs connecting the hangers, links or spring seats secured to the leaf springs and extending inwardly therefrom, a bolster having ends terminating in spring seats within the side bars, means for movably connecting the ends of said links or spring seats with the bolster within its ends, and a spring extending between said bolster ends and said link between the leaf springs and said movable connections. 100

9. In a car truck, the combination with a truck frame, of the longitudinally disposed leaf springs and means for supporting them on the truck frame, links or spring seats secured to the leaf springs and extending inwardly therefrom, ears or extensions on the inner ends of the links, a bolster having pendant lugs located between said ears, a pin for pivoting the said ears and lugs together, the ends of the bolster being provided with spring seats, and a spring extending between said link and said bolster 115 spring seat. 120

10. In a car truck, the combination with a truck bolster, of body supporting springs, inwardly extending spring seats mounted on the body supporting springs and mov- 130

ably connected at their inner ends with the bolster, further spring seats formed in the said links between the body supporting springs and the said movable connection, 5 spring seats formed in the bolster ends, and a spring extending between the link spring seats and the bolster spring seats.

Signed at the city and county of Philadelphia, State of Pennsylvania, this 15th day of August, 1913.

WALTER S. ADAMS.
